UNITED STATES PATENT OFFICE.

ELMER WEBER, OF ELDON, IOWA.

BOX-CAR-DOOR STOP AND FASTENER.

Application filed November 5, 1921. Serial No. 513,067.

To all whom it may concern:

Be it known that I, ELMER WEBER, a citizen of the United States, residing at Eldon, in the county of Wapello and State of Iowa, 5 have invented certain new and useful Improvements in Box-Car-Door Stops and Fasteners, of which the following is a specification.

This invention relates to railroad rolling 10 stock and more particularly to a novel locking and sealing means for the doors of freight cars and the like for preventing the accidental opening thereof due to vibration when the cars are in motion, thereby preventing loss and damage of the articles in 15 transit.

A great deal of shock is sustained by the ordinary hasp and staple used for holding the car door closed when the car is in motion, 20 which often results in the loosening or breaking of the hasp or staple and which allows opening movement of the car doors. This is caused by the shaking back and forth of the door when the car is in motion. 25 Further, after a certain length of time, the stirrup guides at the heel portion of the car door become loose allowing that portion of the door to be swung outwardly a sufficient distance without disturbing the seal at the 30 hasp and staple to permit thieves to remove articles in the car, which may be adjacent to the door.

It is therefore a prime object of this invention to provide a positive means for preventing the jerking back and forth of the car door, when the car is in motion, thereby relieving all strain from the ordinary hasp and staple, and connecting seal, said means also permitting a seal to be associated therewith so that the actuation thereof by unauthorized persons will be prevented.

A further object of the invention is the provision of a novel locking device positioned adjacent to the heel of a sliding car door, so as to prevent sliding movement of the door and lateral movement thereof in relation to the car body.

A still further object of the invention is to provide a device of this character, 50 which will permit the door to be held open a short space, so as to allow the free entrance of air into the car for ventilation purposes, the said means still preventing the sliding movement of the car door in either direction 55 when the door is held in its partly opened position.

A still further object of the invention is to provide an improved lock and stop for sliding doors of freight cars and the like, which is of simple and durable construction, 60 one that can be readily and easily applied to existing freight cars, as well as those in the course of manufacture, and one which can be placed upon the market at a reasonable cost.

With these and other objects in view, the invention consists in the novel construction, arrangement and formation of parts, as will be hereinafter more specifically described, claimed and illustrated in the accompanying 70 drawings, forming a part of this specification, in which drawings:

Figure 1 is a fragmentary side elevation of a freight car with the novel stop and lock associated therewith.

Figure 2 is an enlarged perspective view of the improved lock and stop showing the same applied to a car and car door, and illustrating one of the locking members or bolts being swung in position for engaging 80 the locking bar, and

Figure 3 is a horizontal longitudinal section through a portion of a freight car and door, showing the improved lock and stop applied thereto, the stop and lock being 85 shown in its inoperative position to permit free sliding movement of the door in relation to the car body.

Referring to the drawings in detail, 90 wherein similar reference characters designate corresponding parts throughout the several views, the letter A indicates the improved stop and fastener for a door B of a freight car C.

The door B and the car C, are, of course, 95 of the ordinary construction, and form no part of the present invention, but have simply been shown in order to illustrate the use of the improved stop and fastener.

The door B is slidably mounted in relation to the door opening 5 of the door C by means of an upper longitudinally extending supporting track 6. This suspension means C is also of the ordinary or any preferred type. The lower edge of the door may be 100 guided and held in place by the usual stirrups 7'. The forward edge of the door B is held in its closed position by suitable swinging hasp 7, which is adapted to engage the staple 8. In order to prevent unauthorized 105 movement of the hasp 7 from off of the staple 8, a seal 9 is utilized. The hasp 7, the

staple 8, and the seal 9 are of the usual construction.

The improved stop and locking device A is preferably located adjacent to the heel 5 portion of the car door C, so that the swinging outwardly of the car door C on the track 6 when the guide stirrup irons 7 become loose or broken is obviated.

The improved stop and fastener A consists of a longitudinally extending rigid locking bar 10, which is secured adjacent to the lower edge of the door C. The rigid bar 10 has one end thereof extended beyond the rear or trailing end of the door C and the 15 upper surface of this extended portion of the rigid locking bar 10 is provided with the locking bolt receiving notch 11. The extended portion of the bar 10 having the notch 11 therein is designated by the number 20 a1 12 and its upper surface is provided with a pin receiving opening 13, the purpose of which will be hereinafter more fully described.

A pair of spaced locking bolts or latch 25 bars 14 and 15 are adapted to engage in the notch 11, and each one of these latch bars or locking bolts 14 and 15 is provided with an inwardly extending locking notch 16. These bolts or latches 14 and 15 are held in 30 their spaced relation by means of a spacing block 17, and the latches or locking bolts 14 and 15 are pivotally secured at their lower ends to the spacing block 17 and to suitable angle brackets 18 by means of suitable bolts or pins 19. The bolts or latches 35 14 and 15 are held in their raised position against swinging movement by a T-shaped latch 20 which is pivoted intermediate its ends as at 21' to the spacing block 17, in 40 such a manner that the arms will overlie the outer surface of the latching bars or latches 14 and 15. It can be seen that when it is desired to swing either one of the latches or locking bolts 14 or 15 into engagement with the locking bar 10, that it is 45 merely necessary to operate the latch 20, so as to move the same out of the path of the locking bolt or latch which is to be swung into engagement with the locking bar 10. 50 This permits the locking bolt or latch to be moved into engagement with the locking bar and fit in the notch 11. When one of the locking bolts or latches 14 and 15 is 55 swung into engagement with the walls of the notch 11, it will be seen that the sliding movement of the door C forwardly or rearwardly will be absolutely precluded and that the end walls defined by the notch 16 will also prevent lateral movement of the door 60 toward or away from the body portion of the car.

It is obvious that the door will be held stationary against all movement irrespective of the swinging movement of the car.

65 In the drawings, the improved locking de-

vice and stop has been shown applied to a freight car constructed wholly of steel, but it is obvious that the same can be readily used in connection with wooden cars and in this instance the locking bolts may be fitted 70 in a suitable pocket or notch formed in the outer wall of the car.

When one of the locking bolts or latches 14 or 15 is swung into locking engagement with the lock bar 11, accidental swinging 75 movement thereof is prevented by a hasp 25, which is pivotally connected at its inner end to the latch bar 10 by means of a suitable pivot pin 21. This hasp 25 is adapted to swing over the upper surface of either one of the locking bolts 14 or 15 according to which one is in use, and the end of this hasp is provided with an opening 26, which is adapted to be swung into alignment with the opening 13 or 13'. A pin 27 is adapted to hold 80 the hasp 25 in its operative or inoperative position by inserting the pin through the opening 26 of the hasp and the corresponding opening 13 or 13' of the locking bar 85 which is in alignment with said opening 26. 90 The lower end of this pin 27 may be provided with a diametrically extending opening, whereby a seal 28 may be associated therewith. Thus the removal of this pin 27 and the consequent operation of the locking 95 bolts or latches 14 and 15 will be prevented unless the seal is broken.

When the door B is in its closed position, the notch 11 will be in alignment with the inner locking bolt or latch 14, and thus this 100 bolt is swung into engagement with the walls of the notch and the door will positively be held against movement.

When it is desired to leave the door open a small space so as to permit the entrance of 105 air into the same when the cars are being used for transporting cattle or the like, the door B is moved back to position the notch 11 in alignment with the rearmost locking bolt 15 which is then swung into position 110 with the walls of the notch. Thus, when this latch or locking bolt 15 is swung into its operative position, the door will be held in a slightly open position against movement 115 in any direction.

The location of the improved locking device prevents the swinging out of the lower portion of the door when one of the stirrup irons is broken or loose.

From the foregoing description, it can be 120 seen that an improved and simple device has been provided for adjustably holding a car door against jerking movement whereby the accidental opening thereof due to vibration of the car will be absolutely precluded.

Changes in details may be made without departing from the spirit or scope of this invention; but,

I claim:

1. In a fastening device for sliding doors, 130

- locking means adapted to be secured to the surface over which the door is adapted to slide, means adapted to be carried by the door for engagement with the latching means whereby the door is held in either a closed or partially opened position and accidental movement of the door in any direction in relation to the surface over which the door is adapted to slide is prevented. 60
- 5 2. In a fastening device for sliding doors, locking means adapted to be secured to the surface over which the door is adapted to slide, means adapted to be carried by the door for engagement with the latching means whereby the door is held in either a closed or partially opened position and accidental movement of the door in any direction in relation to the surface over which the door is adapted to slide is prevented, 65 and means for preventing the accidental movement of said latching means. 70
- 10 3. In a fastening device for sliding doors, a latch bar adapted to be pivotally secured to a surface over which a door is adapted to slide, a rigid latch bar carried by the door, the rigid latch bar and the pivoted latch bar having interfitting notches formed therein, whereby lateral movement of the door in relation to said surface will be 75 precluded. 80
- 15 4. In a fastening device for sliding doors, a latch pivotally secured to the surface over which a door is adapted to slide, a rigid latch bar adapted to be carried by the door having a notch in its upper surface for receiving the pivoted latch bar, the latch bar having a notch formed in one of its edges for the reception of the rigid latch bar, and a locking plate pivotally carried 85 by the rigid latch bar for engaging over the upper surface of the pivoted latch bar when the same is swung into engagement with the rigid latch bar. 90
- 20 5. The combination with a surface having a door opening therein, a door slidably carried by said surface for movement toward and away from said door opening, a hasp and staple carried by the door and said surface, the staple being adapted to receive 95 a seal, of means carried by the surface at a point remote from said hasp and staple for engaging the door to prevent movement of said door in relation to said staple whereby accidental movement of the staple, hasp 100 or seal will be prevented. 105
- 25 6. In a fastening device for sliding doors, pivoted latch bars carried by the surface over which a door is adapted to slide for 110 holding the door either in a closed position against lateral movement or in its partly open position against lateral movement. 115
- 30 7. In a fastening device for doors, a pair of pivoted latch bars secured to a surface over which a door is adapted to slide, a rigid latch bar adapted to be secured to the door having a notch therein for the reception of either one of said latch bars whereby the door can be held in various adjusted positions against movement. 120
- 35 8. In a fastening device for doors, a pair of pivoted latch bars secured to a surface over which a door is adapted to slide, a rigid latch bar adapted to be secured to the door having a notch therein for the reception of either one of said latch bars whereby the door can be held in various adjusted positions against movement, and means carried by the latch bar for overlying said notch whereby accidental movement of said pivoted latch bars will be prevented. 125
- 40 9. In a fastening device for sliding doors, a latch bar adapted to be pivotally secured to a surface over which a door is adapted to slide, a rigid latch bar carried by the door having a notch therein for receiving the pivoted latch bar, the rigid latch bar having openings formed therein on each side of said notch, a hasp pivotally secured to the rigid latch bar intermediate said openings, the hasp being adapted to overlie 130 the notch when in one of its positions, the outer end of said hasp having an opening formed therein adapted to register with either one of the openings in the rigid latch bar, and a pin for detachably fitting in said registering openings. 135
- 45 10. In a fastening device for doors, a pair of pivoted latch bars, a spacing block disposed between said latch bars, means adapted to connect the latch bars and the spacing block to a surface over which the door is adapted to slide, means carried by the spacing block for holding the latch bars against swinging movement, each one of the pivoted latch bars having a notch formed 140 therein, a rigid latch bar adapted to be carried by said latch bar and to project rearwardly therefrom, said projecting portion having a notch therein for the reception of either one of said pivoted latch bars and means carried by the rigid latch bar for engaging the pivoted latch bar disposed in said notch for preventing accidental movement thereof. 145

ELMER WEBER.
